UNITED STATES PATENT OFFICE.

THOMAS M. SHANK, OF BIDWELL, OHIO.

GRAIN-CLEANING DEVICE.

1,269,226.

Specification of Letters Patent. Patented June 11, 1918.

Application filed December 22, 1917. Serial No. 208,454.

To all whom it may concern:

Be it known that I, THOMAS M. SHANK, a citizen of the United States, residing at Bidwell, in the county of Gallia and State of Ohio, have invented certain new and useful Improvements in Grain-Cleaning Devices, of which the following is a specification.

This invention relates to grain cleaners and the primary object of the invention is 10 to provide an improved construction for grain cleaning sieves of the type commonly employed on various kinds of grain cleaning machinery.

The principal object of the invention resides in the provision of a removable container carried by the sieve at a point approximately intermediate the ends thereof, and adapted to receive bits of metal which are often found with grain.

20 A further object of the invention is the provision of a device of this character which consists of comparatively few parts and is simple in construction, but durable and well adapted to withstand the rough usage to 25 which devices of this character are ordinarily subjected.

For a full description of the invention and the advantages and merits thereof, reference is to be had to the following description 30 and accompanying drawings wherein is illustrated the preferred form of my invention, in which:—

Figure 1 is a plan view of a sieve showing my invention applied thereto.

35 Fig. 2 is a longitudinal section through the same.

Referring to the drawings, wherein is illustrated the preferred form of my invention, in which like numerals of reference indicate corresponding parts throughout the 40 several views, the sieve indicated generally at A includes the side frame bars 1 and the end frame bars 2. Mounted upon the upper edges of these frame bars is a perforated plate 3 which forms the sieve and which 45 may also consist of a strip of any suitable foraminous material. Intermediate the ends of the strip, a portion of the same is cut away to provide a substantially rectangular opening 4 extending transversely across the sieve. This arrangement provides two end pieces of sifting surface which have their proximate edges spaced apart for a distance equal to the width of the opening 4. These 55 proximate edges are attached to supports 5, the ends of which are fastened in any suit-

able manner to the side frame bars 1. Attached to the bottom of the supports 5, at each end thereof, is a strip of any suitable material as indicated at 6 and these strips 60 are adapted to receive and support a removable receptacle 7 adapted to be placed in the opening 4 and be held between the arms or supports 5 while the bottom of the receptacle rests upon the strips as indicated by dotted 65 lines in Fig. 1 of the drawing. This receptacle is provided on the inner surface of its end wall with a handle 8 which may be grasped for facilitating mounting and removal of the receptacle from the depressed 70 portion of the sieve.

The marginal edges of the sieve, mounted upon the top edges of the frame are held thereto by fastening strips 9 which overlie the margins of the sieve and are fixed to the 75 frame. The strips embrace a portion of the frame in which the grain is received when it is being sifted. During the sifting operation advantage is taken of the fact that most of the bits of metal are heavier than the 80 grain and consequently when the sieve is in operation the objectionable pieces of metal will be worked toward the receptacle 7 and deposited therein while the grain being of lighter weight and also of small size in comparison to the size of the objectionable metal 85 will be sifted through the perforated sifting surface thereby causing only the objectionable metal to be retained in the receptacle 7. The receptacle may be readily removed for 90 dumping the contents thereof, and the grain cleaning surface of the sieve is thereby kept comparatively free of all spurious matter, while the grain is free to sift through the 95 openings therein.

From the foregoing it will be observed that a very simple and durable grain cleaning device has been provided, the details of which embody the preferred form. I desire it to be understood, however, that slight 100 changes may be made in the minor details of constructions without departing from the spirit of the invention or the scope of the claims hereunto appended.

I claim.

1. In a grain sifting sieve, the combination of a frame having a foraminous sifting screen mounted thereon, and a removable receptacle mounted intermediate the ends of the sieve and removably supported by the 110 said frame.
2. In a grain sifting device, the combi-

105

- nation of a frame having a foraminous sieve mounted thereon, the said sieve having an opening provided intermediate its ends extending from one side to the other of the said frame, the supports carried by the frame, and a removable receptacle mounted in the opening and carried by the said support and disposed in a plane below the plane of the said sieve.
- 10 3. A grain cleaning device comprising an elongated sieve having a frame and a strip of foraminous material mounted on the frame, the foraminous material having an opening approximately intermediate its ends

to divide the said sifting surface into the 15 two end portions, the supports carrying the proximate edges of the said portions, and a removable receptacle mounted in the said opening and engageable with the said support, the latter having strips attached thereto for supporting the said removable receptacle.

In testimony whereof I affix my signature in presence of two witnesses.

THOMAS M. SHANK.
